UNITED STATES PATENT OFFICE

JACOB TELLER, OF CHICAGO, ILLINOIS, ASSIGNOR TO TELLER CORPORATION, OF
CHATTANOOGA, TENNESSEE, A CORPORATION OF TENNESSEE

DESIGN FOR A SIDE OVEN FOLDING CLOSED TOP CABINET GAS OR ELECTRIC RANGE

Application filed October 27, 1930. Serial No. 37,393. Term of patent 7 years.

To all whom it may concern:

Be it known that I, JACOB TELLER, a citizen of the United States, residing at Chicago, in the county of Cook and State of Illinois, have invented a new, original, and ornamental Design for a Side Oven Folding Closed Top Cabinet Gas or Electric Range, of which the following is a specification, reference being had to the accompanying drawings, forming a part thereof.

Figure 1 is a front perspective view of the range, showing my new design and Figure 2 is a similar view showing the top raised and folded to form a hood and shelf.

I claim:

The ornamental design for a side oven folding closed top cabinet gas or electric range as shown.

JACOB TELLER.
